UNITED STATES PATENT OFFICE.

HARRY H. HOWELL, OF HOPE, ARKANSAS.

FENCEPOST.

1,359,704.

Specification of Letters Patent. Patented Nov. 23, 1920.

Application filed October 25, 1919. Serial No. 333,172.

To all whom it may concern:

Be it known that I, HARRY H. HOWELL, a citizen of the United States, residing at Hope, in the county of Hempstead and State 5 of Arkansas, have invented a new and useful Fencepost, of which the following is a specification.

This invention relates to novel and useful improvements in fence posts and more 10 particularly to metallic fence posts adapted to be driven into the ground for stringing wires in the construction of fences, the posts being provided with means for attaching the wire thereto.

15 A further and more important object of the invention is to provide novel means whereby when a fence post is driven into the ground, it may be caused to line up properly and perfectly with the remaining posts 20 or adjacent posts of a fence, and so that turning or twisting of the posts or deflection thereof from a perpendicular course or position will be prevented, said means also serving to form a post anchoring means to 25 firmly retain the post in position.

With the above and other objects in view which will appear as the description proceeds, the invention resides in the combination and arrangement of parts and in the details of construction hereinafter described 30 and claimed, it being understood that, within the scope of what is claimed, changes in the precise embodiment of the invention shown can be made without departing from 35 the spirit of the invention.

In the accompanying drawings:

Figure 1 is a perspective view of my improved fence post;

Fig. 2 is an elevation thereof in one position as when being driven into the ground; and

Fig. 3 is a sectional view at right angles to Fig. 2 and showing the post completely driven into the ground.

45 Referring to the drawings in detail, in which like reference characters designate corresponding parts throughout the several views, the numeral 10 designates the post proper, which is made of angle iron or steel, 50 the sides or flanges 11 and 12 of which are disposed preferably at right angles to each other, or other suitable angular relation. One of the flanges is provided with vertically alined spaced openings 13 preferably 55 elongated or slotted to receive staples or other suitable form of securing means for

attaching the fence wires thereto. It is obvious, however, that any other suitable fastening means may be provided for the fence wire.

The lower end of the post is tapered as shown at 14. The opposite flanges are beveled or cut off for this purpose so that the post may be driven into the ground easily and at a very rapid rate. Mounted upon 65 each flange near the lower end of the post and spaced apart one above the other, are substantial triangular or tapered plates 15 and 16, the same being riveted or secured to the side flanges near their upper and lower 70 ends as shown at 17.

The plates 15 and 16 are disposed with their wide edges or ends uppermost and their tapered ends downwardly, said tapered ends being preferably truncated or 75 cut off as indicated at 18, so that as these plates enter the ground, no sharp tapered points will be presented to permit the angular relation of the post to a line of posts to be changed, by turning or twisting of the 80 posts. If these ends were extremely tapered there will be a tendency or possibility of the plates turning in either direction and therefore the lower ends are severed or cut off so that to present a straight edge tending to resist turning of the posts when driven into the ground except under the action of an extraordinary obstruction other than the earth itself, such as a large stone or boulder, 85 roots or the like.

90 The principal objection to all metal fence posts is that it is a hard matter to drive them so that they will line up perfectly and it will be seen that this objection is overcome by the present invention by reason of 95 the two triangular plates or anchors rigidly secured or riveted to the legs of the angle so as to project considerably at either side, except at the extreme lower ends thereof, and at right angles or other suitable angular 100 relation with respect to each other so as to resist the tendency to turn or tilt over in either direction facewise to the plates. Thus, as the post is driven into the ground after being set at the proper point and so 105 that the slotted flange or leg will be disposed in alinement with the other posts and wires to be strung, the lower plate 16 will enter the ground and act as a pilot so that if the post is not in a perfectly upright position, it can be trued up at this point and before the second plate or anchor enters the 110

ground in an untrue position. The first plate being caused to enter the ground properly, the space between the plates will permit the post to be easily turned so that the post may be set true before the second plate enters the ground incorrectly and thereafter serves in conjunction with the first plate to firmly anchor the posts and prevents swaying thereof in either direction or loosing or displacement of the post partly or entirely. The post is preferably made of high carbon steel angle, $1\frac{1}{2}$ " by $1\frac{1}{2}$ " by $\frac{3}{16}$ " in size and of any length to suit the height desired, and the plates forming the anchor are preferably of perfectly flat steel plates preferably of $\frac{3}{16}$ " stock so as to give the required rigidity to permit the post to be driven into the hardest ground with ease. The upper plate or anchor is preferably located with its lower point at least 4" above the top edge of the lower anchor but on the opposite leg, both plates being secured against the outer faces and intermediately of their widths. I am aware that posts have been provided with anchors somewhat similar to the described but said anchors have been provided with a bead, distortion, projecting wing, offset angle, or a variation from the straight plane along the top edge of either of these anchors, but will leave a wide loose path of earth in its wake or above the same when driven into the ground, and will materially hamper the operation of driving in hard or gravelly soil in addition to permitting the post to get loose quickly. By having the plates flat this is prevented and as much resistance is offered in one direction as in the other so that the post will withstand any reasonable amount of strain.

Also, the second or topmost anchor being driven into the ground so that its top edge is just below the surface, and the fact that

its flat surface is riveted to the post on the opposite leg of the angle from the one which carries the slotted holes that receives the 45 staples, and further the fact that the two anchors are set considerable distance apart placing one at the bottom of the hole and the other at the top of the hole, serves to make a very rigid setting, and one that will withstand any reasonable amount of strain from either direction. Another feature of this double anchor construction is that the post will never spiral when driving into the earth, thus leaving the face of the leg of angle at the front of posts, some a little out of line in one direction and some in another, as is the case where a single anchor is used or a full lower anchor and a half upper anchor, as is common in the art.

60

Having thus described the invention what I claim is:

1. The combination with a post having two sides in angular relation, of separate flat plates tapered downwardly and rigidly secured to the respective sides of the post, the lower edge of the upper plate being spaced above the upper edge of the lower plate and both plates having their lower ends cut off horizontally.

65

2. The combination with a post having two of its faces disposed at an angle to each other, of a flat plate secured to each of said faces, the lower end of one plate being spaced above the upper edge of the other plate.

70

In testimony that I claim the foregoing as my own, I have hereto affixed my signature in the presence of two witnesses.

HARRY H. HOWELL.

Witnesses:

Roy ANDERSON,
B. RILEY.
